DWIGHT SLATE, OF HARTFORD, CONNECTICUT, ASSIGNOR TO
PRATT, WHITNEY, & COMPANY, OF SAME PLACE.

Letters Patent No. 89,177, dated April 20, 1869.

IMPROVED SHIPPING-APPARATUS FOR METAL-PLANERS.

The Schedule referred to in these Letters Patent and making part of the same.

To all whom it may concern:

Be it known that I, DWIGHT SLATE, of the city and county of Hartford, and State of Connecticut, have invented certain new and useful Improvements in Shipping Apparatus for Planing Machines; and to enable others skilled in the art to make and use the same, I will proceed to describe, by referring to the drawings, in which the same letters indicate like parts in each of the figures.

The nature of this invention will be understood from the specification and drawings, the object of which is to simplify and make more direct the action of the whole mechanism of the shipping-apparatus of a planer.

It has heretofore been the most difficult part to arrange in a planer, involving many joints, rods, &c.

By this arrangement, many parts heretofore used, are dispensed with, by substituting a rock-shaft, or a rolling, or oscillating cam, secured upon a rock-shaft, which carries or actuates the shipper-rod, thereby rendering it more simple, efficient, and durable.

In the accompanying drawings—

A is a shipper-block, fitted to the projecting edge H of the planer-frame G, so as to traverse back and forth thereon, and is actuated by the common stops, secured upon the side or edge of the bed B.

C is a friction-roller or pin, secured in the block A, directly over, and works in, a zigzag, or spiral groove D, formed in the rolling, or oscillating cam E, which is secured upon the shaft F, that actuates, through the

arm, or segment-gear J, which works in a toothed rack, on the reciprocating-shaft K, the belt-guides I, and thereby changes the motion of the driving-wheels from one direction to the other, thus rendering the action, simple, direct, and positive, and easy to be adjusted, and not liable to get out of order.

I do not wish to limit myself to the particular arrangement of the cam E, because it may be used, under various modifications of arrangement, relatively to the parts acting in connection therewith.

I do not claim a metal-planer, nor do I claim broadly, a shipper-device, for producing a reciprocating or change-motion of a planer-bed.

I believe I have thus shown and described the nature, construction, and advantage of this invention, so as to enable others skilled in the art to make and use the same therefrom.

What I claim, and desire to secure by Letters Patent, is—

The cam E, sliding-block A, in their relation to the reciprocating-planer-bed B, through the stops A', and in combination with the rock-shaft F, arms or segment-gear J, transverse sliding-shaft K, and shipper-arms I, substantially as and for the purpose described.

DWIGHT SLATE. [L. s.]
